REAMER

Filed Feb. 9, 1929

UNITED STATES PATENT OFFICE

LAWRENCE O. BEARD, OF LANCASTER, PENNSYLVANIA

REAMER

Application filed February 9, 1929. Serial No. 338,806.

My invention relates to expandible reamers and more particularly to that class of reamers wherein the blades are integrally formed with the shank of the reamer.

5 The principal object of the invention is to secure maximum expansion of blades with minimum danger of breakage.

Another object is to provide a reamer in which the blades will not become distorted 10 or out of parallel when expanded. I accomplish the above-mentioned and other and more specific objects by the improved construction hereinafter described and claimed.

In the accompanying drawings forming a 15 part of this specification:

Figure 1 is a side elevation of a reamer, embodying the invention, as employed to 20 ream the piston pin bores of an internal combustion engine piston, the piston being shown in outline;

Figure 2 is an enlarged fragmentary view of the reamer, partly in section, showing the means employed in expanding the cutting blades,

25 Figure 3 is a section taken on the line 3—3 of Figure 2.

Figure 4 is a detail of the self feeding member.

Referring more particularly to the drawings wherein the same reference characters 30 indicate like parts in all the figures, 1 represents the reamer having the hollow shank 2, the free end of which is squared as at 3 to facilitate attachment of a wrench or other 35 operating tool. The outer open end of the bore 4, of the shank 2, is internally threaded as at 5 for the purpose of threadedly receiving the reduced threaded portion 8' of a combined pilot and expander 8, the purpose of 40 which will be explained hereinafter.

Cutting blades 6 are integrally formed on the intermediate portion of the shank and in order to impart flexibility to the blades, that is permit expansion and contraction 45 thereof, by means of the pilot expander member 8, elongated slots 7 are cut or otherwise formed. These slots extend through and for a substantial distance beyond each end of that portion of the shank on which the cutting 50 blades are formed and are inclined at a slight

angle to the axis of the reamer. The cutting blades are similarly inclined but to a slightly greater degree than the slots. As a further means of increasing resiliency or flexibility, the slotted portion of the shank adjacent the 55 cutting blades is given a spring temper, that is a softer or lower temper than the cutting blade temper.

When the cutting face of the blades 6 wear down, or when it is desired to increase their cutting capacity, the pilot expander member 8 is screwed home in the bore 4 until the beveled end 9 of the member 8 engages the shoulder 10, thus causing the more flexible or expandible portions or areas adjacent the blades 60 to give. A milled lock nut 11 locks the pilot expander member in adjusted position.

It will be noted from the foregoing that by providing expandible portions adjacent each end of the blades and applying the expanding force or pressure approximately midway the length of the blade portions, that the expansion of the latter will be uniform, that is, the cutting surfaces will always remain on an even plane. Furthermore, as the 70 blade portion of the shank, which is of necessity hard and brittle, is not flexed during the expansion of the cutters, a greater range of expansion is obtained without danger of breaking the blades or blade portions of the 75 shank.

In practice the enlarged threaded portion 8" of the pilot-expander member 8, together with the reamer shank, is inserted through the piston pin bores 12 and 13 of piston 14 in 80 the order named until the cutting blades engage the bushing 15 to be reamed. A centering sleeve 16 is then slipped over the enlarged threaded portion 8" of the pilot-expander member 8 and forced into the bushing 17.

For the purpose of holding the guide sleeve 16 in place and insuring a steady and uniform cutting action, a self feeding member 18 is provided for attachment to the pilot-expander member 8. This feeding member comprises a preferably rectangular bar of metal having a substantially U-shaped recess 19, cut in one edge thereof, the bottom of the recess 95 being semi-circular and threaded, as at 20 100

in effect forming a lead screw nut adapted to receive the threaded portion 8" of the pilot expander member 8. After the feed member 18 has been placed on the pilot-expander member and moved into engagement with the sleeve 16 to snugly clamp the sleeve in the bore 13, the member 18 is held in place by means of a latch member or plate 21 pivotally secured to the member 18, adjacent the recess 19, by means of an adjusting thumb screw 22. The depth of the recess 19 is just sufficient to receive the threaded pilot expander member and the threaded portion 20 of the recess 19 is sufficient in area to engage one half or slightly less than one half of the diameter of the pilot-expander member thread. When the latch member or plate 21 is swung on its pivot to Figures 1 and 4 position, it will close the top of recess 19 and will barely engage the threaded reamer shank, thus holding the same securely to the threads 20 of the recess 19.

Continued turning of the reamer causes the cutting blades 6 to progressively enlarge the bore 12 of bushing 15 as the reamer is fed steadily forward by the feed member 18, rotation of the latter being prevented by engagement of the free elongated end thereof with the vise or work table, not shown, in which the piston is clamped, thus leaving the operators hands free to operate the device.

Having thus described my invention what I claim is:

A reamer comprising a hollow expandible shank, cutting blades formed on said shank, a member having a reduced portion adapted for insertion within said shank for expanding the same, said member having an enlarged threaded portion, a centering sleeve slidably mounted on said enlarged threaded portion and a threaded feeding member for engagement with the said enlarged threaded portion adapted to engage and hold the centering sleeve in place and to feed the reamer and blades when said reamer is rotated.

In testimony whereof I affix my signature.
LAWRENCE O. BEARD.
